[57] **CLAIM**

The ornamental design for a magnifier viewing unit, substantially as shown and described.

DESCRIPTION

FIG. 1 is a side perspective view of a magnifier viewing unit, with its shade open, showing my new design; FIG. 2 is a front perspective view made from the right side thereof;

FIG. 3 is a rear perspective view from the right side thereof;

FIG. 4 is a front and side perspective as seen from the side opposite to that of FIG. 1; and

FIG. 5 is a front and side perspective, similar to FIG. 2, with the shade closed.

FIG. 1

FIG. 2

FIG. 3

FIG. 4

FIG. 5
